(57) **CLAIM**

We claim the ornamental design for the spring head assembly for faucet, as shown and described.

DESCRIPTION

FIG. 1 is a perspective view of the spring head assembly for faucet showing our new design with the broken lines shown for illustrative purposes only and forming no part of the claimed design;

FIG. 2 is a front elevational view thereof;

FIG. 3 is a right-side elevational view thereof;

FIG. 4 is a left-side elevational view thereof;

FIG. 5 is a back elevational view thereof;

FIG. 6 is a top plan view thereof; and,

FIG. 7 is a bottom plan view thereof.
